UNITED STATES PATENT OFFICE.

DORR E. FELT, OF CHICAGO, ILLINOIS.

KEY FOR KEYBOARD CALCULATING-MACHINES.

982,416.

Specification of Letters Patent. Patented Jan. 24, 1911.

Application filed April 4, 1910. Serial No. 553,364.

To all whom it may concern:

Be it known that I, DORR E. FELT, a citizen of the United States, residing in Chicago, in the county of Cook and State of Illinois, have invented a new and useful Improvement in Keys for Keyboard Calculating-Machines, of which the following is a specification.

This invention relates to the construction of the keys of calculating or other machines having keyboards whereby they are operated or controlled. It is desirable in operating these machines that the operator place his finger squarely on the center of the keys, because in that way he avoids depressing adjacent keys with the key he wishes to operate.

To avoid mistakes of this kind has been my object in this invention, and to this end I provide the keys with locking mechanism which can only be released by pressing upon the center of the keys. The releasing devices are so located that they are depressed necessarily when the finger presses properly on the center of the key, but they are not depressed when the operator presses on the margin of the key instead of the center. In the latter case, of course, the key is not released and cannot be operated.

The nature of my invention is fully illustrated in the accompanying drawing and also described below, and in said drawing—

Figure 1 is a partial longitudinal vertical section of a comptometer having my present improvement. Fig. 2 is a section on the line 2—2 of Fig. 1. Fig. 3 is a top view of the key. Figs. 4 and 5 are vertical views of portions of the mechanism and Fig. 6 is a horizontal section on the line 6—6 of Fig. 2. I have shown the invention as applied to a comptometer constructed in accordance with the invention disclosed in my pending application No. 453271 filed September 16, 1908.

In said drawing, 7 represents one of the series of segment levers adapted to be depressed by the series of keys 8 belonging to the same denomination as the lever. The lever shown operates a pinion 9, and through the intermediate pinion 10 the motion of pinion 9 is transmitted to the numeral wheel 11 in the customary way. The stems of the keys extend to the bottom of the machine and are there provided with lifting springs

12 by which they are returned to normal 55 position after each actuation.

At 13 is one of a series of longitudinal bars, supporting a series of pivot rods 14 extending transversely of the machine and supporting the rocking key locking devices 60 15, of which latter there is one for each key. These key locking devices will be understood from Fig. 4 and they are provided with wings 16 at the bottom having openings through which the rods 14 may pass, with 65 sloping shoulders 17 at the top whereby they are caused to swing to release the keys, and with straight faced shoulders 18 whereby they lock the keys. To operate the devices 15, I provide the key with a centrally located releasing device which when it is depressed with the key necessarily operates the device 15 and effects the release of the key, but which is not depressed with the key unless the pressure from the finger of 70 the operator comes directly on the releasing device. This releasing device consists of tube 19 placed between the limbs of the forked top 20 of the key stem and capable of a limited sliding movement independent 80 of the forked top, a button 21 loosely fitting an opening formed in the top of the key and having a stem 22 depending therefrom, and a spring 23 in the tube and confined in it by the cross pin 24 at the top and by the 85 crotch 25 of the forked key stem at the bottom. The pin 24 passes through the stem 22 and its ends are extended under the bottom of the key top 27 so that the button cannot be forced upward by the spring beyond its normal position, and the tube 19 is slotted at the bottom so that it can move downward beyond the crotch 25, and the tube is so located that when depressed its bottom encounters the sloping shoulder 17 90 of the locking device and swings said device from its locking position.

With this construction the operation is as follows:—When the operator presses on the key with his hand bearing on the button 21, 100 he depresses the button so that the tube is caused to strike the sloping shoulder of the locking device and effect the immediate release of the key so that the movement of the key which immediately follows will be unobstructed. But if the operator should fail thus to depress the button 21, his pressure on the margin of the key will simply cause

the key to descend until the shoulder 28 of the key stem bears on the shoulder 18 of the key locking device, which of course stops all further movement.

5 While I have devised this invention more especially for use on key board calculating machines, it will be obvious that it can be used on any machine having keys for operating or controlling its action.

10 The locking devices are each provided with springs 16^a attached at one end to the wing 16 and at the other end to the bars 13 as shown, and such springs serve to keep the locking devices in normal position.

15 I claim—

1. The combination in the keyboard of a calculating or other machine, of a series of keys, a series of locking devices, one for each key, whereby the keys are normally locked, 20 and means within each key whereby it will be released when struck.

2. The combination in the keyboard of a calculating or other machine, of a series of keys, and a series of locking devices one for 25 each key, whereby the keys are normally locked, and means for releasing the keys actuated by pressure on the top of the keys.

3. The combination in the keyboard of a calculating or other machine, of a series of keys, and a series of locking devices one for each key, whereby the keys are normally locked, and means for releasing the keys actuated by the pressure of the finger in the 30 act of depressing the keys.

35 4. The combination in the keyboard of a calculating or other machine, of a series of normally locked keys and a series of locking devices, one for each key, and devices for

releasing said locking devices, the last named devices being operable by pressure on the 40 tops of the keys.

5. The combination in the keyboard of a calculating or other machine, of a series of normally locked keys, and a series of locking devices, one for each key, and devices for 45 releasing said locking devices, the last named devices being located in the centers of the keys and accessible at the tops thereof.

6. The combination in the keyboard of a calculating or other machine, of a series of 50 normally locked keys and their locking devices, each of said keys being provided with means whereby when properly struck at the center will cause its release.

7. In a keyboard, a finger key made in two 55 parts, both adapted to be depressed by the finger when actuating the key, one of said parts being movable with respect to the other part and its actuation being necessary to the operation of the key, whereby danger of the 60 accidental actuation of a wrong key with the one struck is largely prevented.

8. In a keyboard, a finger key made in two parts, both adapted to be depressed by the finger when actuating the key, one of said 65 parts being located at the center of the key top and being movable with respect to the other part and its actuation being necessary to the operation of the key, whereby danger of the accidental actuation of a wrong key 70 with the one struck is largely prevented.

DORR E. FELT.
